UNITED STATES PATENT OFFICE.

CHRISTOPHER H. G. HART, OF LOS ANGELES, CALIFORNIA.

TOY VEHICLE.

Application filed March 10, 1926. Serial No. 93,575.

This invention relates to a new and useful toy vehicle.

An object of the present invention is to provide a toy vehicle which is adapted to travel along the ground with a motion simulating the motion of a horse.

In accordance with the present invention, the vehicle is provided with a body simulating that of an animal such as a horse, together with a driving means, whereby the rider of the vehicle may propel the same along the ground and in addition thereto, the body of the vehicle is mounted upon a steel spring bar so that the body is adapted to spring upwardly and downward as it travels, thereby to provide not only a straight forward motion to the vehicle but also to simultaneously permit an upward and downward rocking or springing of the body and operator during the travel.

Various objects and advantages of the invention will appear from a description of a preferred form or example of a toy vehicle embodying the invention. For this purpose, reference is made to the accompanying drawings, in which:

Figure 1 is an elevation of the vehicle,

Figure 2 is a plan view of the vehicle with the body removed,

Figure 3 is a front elevation of the vehicle with the body removed,

Figure 4 is a detail of the rear wheel construction,

Figure 5 is an enlarged fragmentary view of the front of frame, and,

Figure 6 is an enlarged elevation of the chain take up means.

Referring to the drawings, the vehicle comprises a body 2 shaped to simulate that of a running animal, such as a horse, the body 2 being provided with a seat 3. The vehicle also includes a frame 4 provided with front wheels 5 and a rear wheel 6. There is also provided driving means 7 which may be connected either to the front wheels 5 or the rear wheel 6, being indicated as connected with the front wheels 5. Said driving means 7 is indicated as comprising a chain 8 connected by a gear 9 to a shaft 12 which is rigid with the front wheels 5 and being connected by a gear 10 to a shaft 11 journaled in the body 2 of the vehicle, which shaft is provided with driving pedals 12 at opposed sides of the body 2, and in convenient position for operation by an operator mounted upon the seat 3. Suit-

able means are provided by which the slack in the chain 8 may be automatically taken up, said means being indicated as comprising springs 13 mounting rollers 14 engaging the inner sides of the chain 8.

The running frame 4 may be of any desired or preferred form of construction, being preferably provided with a longitudinal member 15 which, at the front end of the vehicle, is rounded, as indicated at 16, and the body 2 of the vehicle is secured to and mounted on the frame 4 by means of a steel spring bar 17, one end of which is attached to the longitudinal member 15, as indicated at 18, and curves at least partially around the rounded portion 16 of the longitudinal member 15. The bar 17 extends from said rounded portion 16 upwardly and rearwardly and is, at its upper end, suitably attached to the body 2 by means such as indicated at 19. By this construction, the body 2 is adapted to spring up and down with respect to the running frame 4 with the steel spring bar 17 bending around and supported by the rounding portion 16 of the longitudinal member 4 thereby supporting the bar 17 against possible fracture from such action.

The vehicle is provided with suitable guiding means which preferably is in the form of reins 20 extending from the mouth of the body of the vehicle down to the seat 3 and thence down to rollers 21 mounted by the front part of the running frame of the vehicle and hence to the rear wheel 6 of the running frame, which is mounted upon a shaft 22 which is journaled to the running frame 4.

The toy vehicle thus described may be driven along the ground by an operator on the seat 3 through propelling the vehicle by rotation of the pedals 12. The body 2 supporting the rider may, during this travel, be rocked or sprung up and down with respect to the running frame 4 of the vehicle with the result that an action closely resembling that of a running animal. It will be noted that the body 2 being mounted upon an upwardly and rearwardly inclined steel bar, that its up and down motion with respect to the running frame 4 is also accompanied by a slight fore and aft rocking of the body 2.

While the particular form of the invention herein disclosed is well adapted to accomplish the objects of the invention, the invention may be embodied in other forms,

and is of the scope set forth in the appended claims.

I claim:

1. In a toy vehicle, the combination with a wheeled running frame, and a body providing an operator's seat, driving means for propelling the vehicle, adapted for operation independent of the rocking of the body, and an upwardly and rearwardly inclined spring bar supporting the body on the running frame, said spring bar constituting the sole supporting means for said body.
2. In a toy vehicle, the combination with a wheeled running frame, of a body simulating that of an animal, an upwardly and rearwardly inclined steel bar supporting said body on the running frame, and driving means adapted for propelling said vehicle, said running means including a chain drive, and spring means for taking up the slack of said chain drive.
3. In a toy vehicle, a wheeled running frame, a spring bar secured at one end to the running frame and extending upwardly

at an incline, the upward end of the spring bar being free, a body supported on the spring bar and simulating the appearance of a running animal, and propelling means secured to the body and having a driving connection with the wheel base, and spring take-up means for said driving connections.

4. In a toy vehicle, the combination of a wheeled running frame, a spring bar connected at one end to the running frame and extending upwardly at an incline, the upper end being free, a body mounted on the upper end of said spring bar, said spring bar constituting the sole supporting means for said body, a driving means supported by the body, adapted for operation independent of the rocking of the body, a driving connection between said wheeled frame and said driving means, and a steering mechanism for said vehicle.

Signed at Los Angeles, California, this 25 day of February, 1926.

CHRISTOPHER H. G. HART.
